UNITED STATES PATENT OFFICE.

FREDERICK G. FLETCHER, OF BURLINGTON, VERMONT.

DESIGN FOR A WATCH-CHAIN.

SPECIFICATION forming part of Design No. 24,161, dated April 2, 1895.

Application filed March 24, 1894. Serial No. 505,012. Term of patent 7 years.

To all whom it may concern:

Be it known that I, FREDERICK G. FLETCHER, a citizen of the United States, residing at Burlington, in the county of Chittenden and State of Vermont, have invented and produced a new and original Design for Watch-Chains, of which the following is a specification, reference being had to the accompanying drawings, forming part thereof.

10 My invention has relation to designs for watch chains, especially to be used as fobs, which are fully described and illustrated in the accompanying drawings and specification, in which—

15 Figure 1 is a front view of the chain. Fig. 2 is a rear view of the same.

This design is more particularly intended for leather chains or fobs, but may be used in

other chains, each link A flat in plan view and having a contour comprising an opening *b* at 20 one end, and a reduced portion *c*, at its opposite end, and an opening *d* between the inner end of the opening *b* and the reduced portion *c*.

Having thus described my design, what I 25 claim, and desire to secure by Letters Patent, is—

The design for a watch chain, substantially as herein shown and described.

In testimony whereof I do affix my signature in presence of two witnesses.

FREDERICK G. FLETCHER.
